[57] CLAIM

The ornamental design for a combined makeup mirror and brush box, substantially as shown.

DESCRIPTION

FIG. 1 is a front perspective view of a combined makeup mirror and brush box showing my new design;
FIG. 2 is a side elevational view thereof;
FIG. 3 is a rear elevational view thereof;
FIG. 4 is a bottom plan view thereof;
FIG. 5 is a perspective view thereof in a fully opened position;
FIG. 6 is a side elevational view thereof in the fully opened position; and
FIG. 7 is a top plan view thereof in the fully opened position.
